UNITED STATES PATENT OFFICE.

FRANKLIN P. EASTMAN, OF NEW YORK, N. Y.

SIDE-DUMPING BOAT.

Application filed August 11, 1922. Serial No. 531,210.

To all whom it may concern:

Be it known that I, FRANKLIN P. EASTMAN, a citizen of the United States, and a resident of the city of New York, borough 5 of Manhattan, in the county and State of New York, have invented a new and Improved Side-Dumping Boat, of which the following is a full, clear, and exact description.

10 This invention relates to scows or boats and particularly to boats which will dump from the side.

15 The object of the invention is to provide a side dumping boat which may be easily dumped and easily re-set for a new load.

20 Another object of the invention is to provide a side dumping boat or scow for use in dumping garbage, trash or other loads in the sea, the arrangement being such that the 25 sides will swing outwardly and downwardly during the dumping operation so that there will be a quick release of the load on both sides in order that the equilibrium of the boat may be maintained.

25 A still further object of the invention is to provide a side dumping boat in which means are provided which will permit the doors or side members to be quickly swung back to their former operative position.

30 In the accompanying drawings—

Figure 1 is a top plan view of a boat disclosing an embodiment of the invention, certain sections of the boat being shown in a dumped position.

35 Figure 2 is a side view of the structure shown in Figure 1.

Figure 3 is a sectional view through Figure 1 approximately on line 3—3.

40 Figure 4 is a detail perspective view of a compensating lever.

Figure 5 is a perspective view of a brace embodying certain features of the invention.

45 Figure 6 is a sectional view on an enlarged scale through Figure 1 approximately on line 6—6.

Figure 7 is a sectional view through Figure 1 approximately on line 7—7, the same being on an enlarged scale with certain parts broken away.

50 Figure 8 is a fragmentary view of the beam supporting the ratchet, pawl and handle for its actuation.

55 Referring to the accompanying drawings by numeral, 11 indicates the boat or scow which is provided with a bottom 12 of any usual or preferred construction and

a number of braces or beams 13 of any desired construction. The bottom 12 is connected with the side walls 14 and 15 of suitable construction, said side walls extending 60 a short distance above the bottom where they merge into the inclined bottoms 16 and 17, said bottoms having the appearance of an A in cross section as illustrated in Figures 3, 6 and 7. At each end of the bottoms 65 16 and 17, there is a bulkhead and these bulkheads are designated by the reference characters 18 and 18'.

Along the top edges of the side walls 14 and 15 are hinged a plurality of doors 23 70 and 24, there being in the present instance four doors on each side of the boat.

As indicated in Figures 6 and 7, when these doors are closed or in a vertical position, the sides of the boat are closed and 75 ready to receive a load. When it is desired to discharge this load, these doors are released and allowed to move down under the action of gravity and the pressure of the load until they assume substantially the position shown in Figure 3. This will allow the load to slide off into the water automatically. This construction and arrangement of side dumping boat may be used for various purposes but it is particularly adapted 85 for transporting matter to the ocean and dumping the same thereinto.

After the load has been dumped, the chains 25, 26 and 27 are wound on their respective drums 28, 29 and 30. These 90 drums may be of any suitable kind and mounted upon a shaft 31 supported by suitable standards and operated by a ratchet wheel 32 rigidly secured to shaft 31. The ratchet wheel 32 is engaged by a suitable 95 pawl 33 for normally preventing a reverse movement and engaged by a pawl 34 operated by a lever 35 for rotating in a direction for raising the doors 23 and 24. It will be noted from Figure 3 that suitable guide rollers 36 and 37 are provided to guide the chains on the opposite sides of the boat to their respective drums. As all of the gates and associated parts are identical, the description of one will apply to all. 100

105 In view of the fact that the respective gates usually move past a central line when swinging downwardly to an open position, it will be difficult, if not impossible, for a chain to raise these gates if secured to the upper end of the gates or doors. To overcome this difficulty, the respective chains 26 110

are connected with one end of a fulcrum bar 38, said fulcrum bar at the opposite end being pivotally connected at 39 with a pair of links 40, which links in turn are pivotally connected to the pintle 41 of the hinges 42 supporting the gates. As this fulcrum bar is comparatively light and moves on the link 40, it may be readily swung upwardly to the dotted position shown in Figure 3 when the 10 chain 26 is pulled. A connecting chain 43 is connected to the upper end of the door or gate 23 and to the outer end of the fulcrum lever 38 so that as soon as the parts assume the dotted position shown in Figure 3 any 15 additional pull on the chain 26 will cause the gate 23 to move upwardly on its hinge 42. This upward movement is continued under the pull of the chain 26 until the parts assume substantially the position shown in 20 dotted lines in Figure 7. When the parts are in this position, the strain is transferred to the respective chains 25 and 27 which finish the closing movement of the doors. It will be noted that these chains are connected 25 to the respective bracing bars 44, said bracing bars being pivotally mounted at their outer ends to the upper edge of the doors and at their inner ends provided with enlargements 45 designed to abut against the 30 stop 46.

By this construction and arrangement the bracing bars 44 act as elevating means for a short distance and then act to hold the door against either inward or outward 35 swinging movement. The chains 26 and 43 are so proportioned as to be automatically taken up as the respective chains 25 and 27 close the door. Usually the fulcrum lever 38 assumes the position shown in Figure 6 40 when the gate has been completely closed. As indicated in Figure 3, the respective chains 25 and 27 are proportioned to be very slack when the gates are completely open in order that the drums may properly wind up 45 these chains and chain 26 simultaneously.

As indicated in Figures 3, 6 and 7, a platform 47 is provided beneath the inclined floors 16 and 17, said platform providing ample space for a workman when actuating 50 or releasing the doors. Preferably there is but one workman since when operating a boat of the size shown in Figure 1, only one workman will be necessary to release the doors and again restore them. By quickly 55 and automatically releasing the doors on opposite sides of the boat, the load will be discharged evenly on opposite sides of the boat and will, consequently, not cause the boat to list even if the sea is rough. Also, this arrangement of releasing and closing of the doors may be readily performed in almost any kind of a sea, that is, whether the waves are high or low. It will be noted that the boat will be very buoyant in view of the hol-

low construction caused by the arrangement 65 of the various floors 12, 16 and 17.

What I claim is:

1. In a side dumping boat of the character described, a boat body formed with inclined members, a plurality of doors hinged to the boat body at the bottom of said inclined floor members, said doors when in a vertical position acting as side walls, a plurality of chains connected with said doors, drums for actuating said chains for causing 75 the chains to close the doors, and a pulling and bracing bar normally extending between the free end of the door and the upper end of the inclined members for each door for limiting the closing action. 80

2. In a side dumping boat of the character described, a plurality of doors acting as sides to the boat, each of said doors being hinged to the boat to swing in a vertical plane, chains connected with each of the 85 doors for closing the same, and a pair of auxiliary chains for assisting in closing each door, bracing rods interposed between the respective doors and said auxiliary chains, said bracing rods being hinged at one end to the respective doors, and stops carried by the boat for engaging one end of the bracing rods for limiting the closing action of the auxiliary chains. 90

3. In a dumping boat of the character described, a plurality of hinged doors, and means for closing said doors, said means including a drum, a chain adapted to be wound on said drum, a fulcrum lever pivoted to the boat and connected at one end to said chain, 100 a connecting chain connecting said lever with the outer end of said door, and means for rotating said drum whereby said chain will be wound on the drum and the chain will first swing the fulcrum lever to a given 105 point and then act on the fulcrum lever and said connecting chain for swinging the door to a closed position. 110

4. In a side dumping boat of the character described, a hinged door forming part 110 of the side of the boat, and means for closing said door, said means including a drum, means for rotating said drum, a chain adapted to be wound on said drum, a fulcrum lever having its outer end connected 115 with said chain, a link pivotally connected to the inner end of said fulcrum lever and to said boat, and a connecting chain connecting the outer end of said lever with the upper edge of said door whereby when the door is 120 open and said drum is rotated the chain will be pulled and will swing the fulcrum lever a predetermined distance first and then will act on the fulcrum lever and said connecting chain for swinging the door to a closed position. 125

FRANKLIN P. EASTMAN.
